[57] **CLAIM**

The ornamental design for an animal blocking end for downspouts, as shown and described.

DESCRIPTION

FIG. 1 is a perspective view taken from the top, front and left side of an animal blocking end for downspouts showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof; and,

FIG. 8 is a perspective view taken from the top, front and left side of a modified form of the animal blocking end for downspouts shown in FIG. 1.

The fragmentary broken line representation of a downspout in FIGS. 1 and 8 are for purposes of illustration only and form no part of the claimed design.
